STERILIZATION INDICATOR TAPE

Arthur W. Kelson, New York, N.Y., assignor to Propper Manufacturing Co. Inc.

Filed Apr. 15, 1971, Ser. No. 134,521

Term of patent 14 years

Int. Cl. D24—99

U.S. Cl. D83—1 W

The figure is a plan view of a sterilization indicator tape showing my new design.

The gauge of the tape is of no substantial thickness and the pattern is understood to be uniformly repetitive.

I claim:

The ornamental design for sterilization indicator tape, as shown and described.
